UNITED STATES PATENT OFFICE.

THOMAS CROXTON BEAZLEY, OF RICHMOND, VIRGINIA.

HEEL-PLATE FOR RUBBER HEELS.

1,153,368.

Specification of Letters Patent. Patented Sept. 14, 1915.

Application filed January 31, 1913. Serial No. 745,365.

To all whom it may concern:

Be it known that I, THOMAS CROXTON BEAZLEY, a citizen of the United States, residing at Richmond, in the county of Henrico and State of Virginia, have invented 5 certain new and useful Improvements in Heel-Plates for Rubber Heels, of which the following is a specification.

My invention relates to heel plates for 10 rubber heels for boots and shoes; and its object is to provide a metal heel plate which may be readily attached to the rubber heel of a boot or shoe.

In the accompanying drawings, which 15 form a part of this specification, and in which like numerals refer to like parts in the several views:—Figure I shows the heel of a shoe in elevation, and partly in section; Fig. II shows the same, in plan; and Fig. 20 III is a perspective view of the heel plate.

Referring to the drawings:—1 is a rubber heel, attached to the leather heel of a shoe by means of nails 2. The rubber heel is provided with holes 3, at the inner ends of 25 which there are formed cavities 4, in which are embedded washers 5. When the rubber heel is to be attached to the shoe, after it is set in place nails are entered in the holes 3, and in the holes in the washers 5, 30 and are then driven through the solid rubber beyond, and into the leather of the shoe heel, until the heads of the nails bear upon the washers.

It should be noted that though the washers 35 5 are larger in diameter than the holes 3, they may, on account of the elasticity of the material forming the heel, be withdrawn through the holes 3, and even be replaced in the cavities.

40 In the course of time rubber heels will wear, as do heels of other material; and to provide against this wear I use the heel plate 6, which is formed of steel or other suitable material.

45 My heel plate comprises the plate portion 6, from each end of which extends an arm 7, formed practically at right angles to the plate 6. At the other ends of the arms 7 there are formed, integral with the arms,

washers 8, similar in form and size to the 50 washers 5 commonly used with rubber heels.

The washer shaped ends 8 of the heel plate are at such a distance apart that they may be forced into two of the holes provided in the rubber heel, as shown in Figs. I 55 and II.

When it is desired to attach my heel plate to the rubber heel, the old nails from two of the holes 3 are withdrawn, and the old washers are also withdrawn. The washer ends 8 60 of the heel plate are then driven by means of a simple punch, one into each of the holes from which the old nails and washers have been removed. Nails are now entered in the said holes, and in the holes provided in 65 the washer ends 8 of the heel plate, and are driven through into the leather heel of the shoe. In this way the heel plate is attached to the heel of the shoe.

It will be readily understood that my heel 70 plate may be attached to a newly applied rubber heel to prevent wear; or to a rubber heel that has been in service and has become worn.

Though I have shown and described my 75 heel plate in connection with only one form of rubber heel, it may be attached to rubber heels of other types. For instance, to apply my heel plate to rubber heels not provided with nail holes and washer cavities, it is 80 only necessary to make in the rubber heel holes into which the washer ends 8 of the heel plate may be forced. The heel plate is then applied, and secured by means of nails, in the manner described above. 85

It will be observed that the elastic heel is provided with openings of the size to fit the heads of the fastening and contiguous with the heads these openings enter the enlarged cavities which receive and retain the washers 8, forming the terminals of the arms 7, thus fitting the plates in proper position.

Having described my invention, what I claim, and desire to protect by Letters Patent of the United States, is:—

The combination, in a heel, of a leather heel member, an elastic heel or lift member having vertical openings formed with en-

larged horizontally disposed cavities, a flat plate having a lateral curved portion forming a broad wear surface, and formed with vertical arms terminating in horizontal perforated members fitting in the horizontal cavities of the elastic lift, and headed fastenings having their heads arranged in the openings of said elastic lift and passing

through the perforations of said horizontal members into the leather heel. 10

In testimony whereof I affix my signature, in presence of two witnesses.

THOMAS CROXTON BEAZLEY.
